(57) **CLAIM**

The ornamental design for an electric bike, as shown and described.

DESCRIPTION

FIG. 1 is a first perspective view of an electric bike, showing my design.

FIG. 2 is a second perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of a circle labeled 9 in FIG. 1 of the electric bike.

FIG. 10 is an enlarged view of a circle labeled 10 in FIG. 1 of the electric bike.

FIG. 11 is an enlarged view of a circle labeled 11 in FIG. 1 of the electric bike.

FIG. 12 is an enlarged view of a circle labeled 12 in FIG. 2 of the electric bike.

FIG. 13 is an enlarged view of a circle labeled 13 in FIG. 2 of the electric bike.

FIG. 14 is an enlarged view of a circle labeled 14 in FIG. 2 of the electric bike.

FIG. 15 is an enlarged view of a circle labeled 15 in FIG. 5 of the electric bike; and,

FIG. 16 is an enlarged view of a circle labeled 16 in FIG. 6 of the electric bike.

The broken lines are for environmental structure or boundaries only and form no part of the claimed designs to be patented.

1 Claim, 16 Drawing Sheets
